LIGHTER CONSTRUCTION

Carl Julius Lagerholm, Attleboro, Mass., assignor
to Evans Case Company, North Attleboro,
Mass., a corporation of Massachusetts

Application August 4, 1928, Serial No. 297,388

7 Claims. (Cl. 67—7.1)

This invention relates to lighting devices, and more specifically to those in which a wick is ignited by sparks from pyrophoric metal.

One of the objects thereof is to provide a practical device of the above type of simple and durable construction. Another object is to provide a device of the above type in which the action is efficient and dependable. Another object is to provide a device of the above type which shall be economical in the use of material and in which, nevertheless, the ignition is rendered certain in a manually convenient manner. Another object is to provide a device of the above type which shall be adapted to meet the most severe conditions of use without injury or loss of effectiveness. Other objects will be in part obvious or in part pointed out hereinafter.

The invention accordingly consists in the features of construction, combinations of elements, and arrangements of parts which will be exemplified in the apparatus hereinafter described and the scope of the application of which will be indicated in the following claims.

In the accompanying drawing, in which is shown one of various possible embodiments of this invention,

Figure 1 is a sectional elevational taken substantially along the line 1—1 of Fig. 4;

Fig. 2 is a sectional elevation taken along the line 2—2 of Fig. 1;

Fig. 3 is a vertical sectional view taken along the line 3—3 of Fig. 4, it being understood that in Figs. 1 and 3 additional parts are shown which, for the sake of clearness, are omitted from Fig. 4;

Fig. 4 is a sectional plan taken along the line 4—4 of Fig. 1;

Fig. 5 is a sectional elevation taken along the line 5—5 of Fig. 1;

Fig. 6 is a detailed elevation of certain parts shown in Fig. 3 and appearing in a different position; and

Fig. 7 is a vertical sectional elevation taken along the line 7—7 of Fig. 1.

Similar reference characters refer to similar views throughout the several figures of the drawing.

Referring now to the drawing in detail, there is shown a fuel tank comprising the top wall 10, bottom wall 11, and side walls 12. This tank is provided with the customary filling of absorbent material 13, and its bottom wall has threaded therein a removable plug 14 covering an opening through which liquid fuel may be poured in when the tank is inverted.

Within the tank is mounted an absorbent wick

15 of asbestos or the like which passes through a constricted passage formed by a tube 16 extending downwardly for a substantial distance into the tank and upwardly through the upper wall 10. A virtual continuation of the inner surface of this tube is formed in a boss 17 which in turn is formed on the upper surface of the top wall 10 and provided with a stop shoulder 18 for a purpose hereinafter described. In this manner the wick, although adapted for excellent capillary action to feed its upper exposed end 19, is nevertheless constricted so as to tend to prevent the passage of liquid fuel therethrough when the tank is inverted and filled. Furthermore, when this filling action takes place with the tank inverted 15 and the plug 14 removed, there is often an excess of liquid fuel accumulating adjacent the top wall 10 (then the bottom wall). This liquid fuel, due to inevitable supersaturation of the mass 13, would tend to flow out through the wick and 20 cover the parts adjacent its upper end tending to reduce their efficiency in action and possibly causing the device to catch fire for a short time until this coating of fuel is exhausted. With this arrangement, however, when the tank is inverted, 25 the tube 16 extends upwardly to such a distance that no ordinary accumulation of liquid fuel can overflow its top edge and tend to pass downwardly toward the free end 19 of the wick.

Formed upon the upper surface of the top wall 10 are a pair of webs 20 and 21. Journaled in these webs is a shaft 22 having loose thereon a pinion 23 and having loosely mounted thereon a cam wheel 24 fixed to an abrasive wheel 25, the latter being intermediate the pinion and cam wheel, as shown in Fig. 7 of the drawing. Forced upwardly against the lower surface of the friction or abrasive wheel 25 is a short cylindrical piece of pyrophoric metal 26 which is urged toward the wheel by a long spiral spring 27 resting within the tube 28, the lower end of which is closed by a removable plug 29 threaded into the tube and passing through the bottom wall 11. Thus, upon the wheel being rotated in a clockwise direction, as viewed in Fig. 1, its teeth formed for abrasive action in operation throw a shower of sparks upwardly toward the left, it being understood that the member 26 is slightly displaced toward the left with respect to the axis of the wheel.

A snuffer member 30 is provided with a pair of 50 depending ears 31 and 32 journaled upon the shaft 22, and the latter of which has fixed thereto the pinion 23. The cap 33 of the snuffer fits tightly at its lower end the shoulder 18 and thus seals in the exposed wick end 19, preventing evap- 55

oration or waste of fuel therefrom. The member 30, however, can swing upwardly to the position indicated in dotted lines in Fig. 1 of the drawing upon rotation of the pinion 23.

5 The snuffer member 30 is provided with a cross-pin 34 having fixed thereon a dog 35, and a small spiral spring 36 about the pin 34 tends to swing the dog downwardly and toward the right so as to hook into engagement with the 10 teeth of the cam wheel 24 as best shown in Fig. 3 of the drawing. The action of these teeth and related parts will later be described in detail.

A pivot pin 37 is mounted in the webs 20 and 21 spaced from and substantially parallel to the 15 pin 22. Upon this pivot pin is loosely mounted an actuating device 38 provided with an extension 39 which rests within a recess 40 formed in the top wall 10 and terminates in a short curved rack 41 provided with internal gear teeth suitably 20 meshing with the pinion 23. Normally, the actuating device 38 is urged upwardly by a heavy spiral spring 42 coiled about the pin 37 and compressed between the top wall of the tank and the under surface of the channel-shaped finger grip 25 43 formed at the end of the actuating device. This spring tends to swing downwardly the rack 41 and likewise press against its seat the snuffer cap 33, a stop being expressly omitted so as to insure a tight fit of the snuffer cap. If, however, 30 the finger portion 43 is pressed downwardly, the upward movement of the rack 41 whirls the pinion 23 and swings upwardly the snuffer cap. In depressing the part 43 to cause this movement, any tendency of the thumb or finger to slip off 35 the end of this part is precluded by its upwardly curved upper surface. Furthermore, the upwardly curved lower surface, as indicated at 44, permits an additional angle of movement of the actuating device before it is stopped by engagement with the upper surface of the top wall 10. 40 Thus both of these curved surfaces perform an important beneficial function.

As the snuffer cap is swung upwardly, as above described, the dog 35 pulls upwardly upon the 45 teeth of the cam wheel 24 with which it is interlocked, as shown in Fig. 3. This movement is retarded by a resilient member 45, here shown in the form of a flat spring having a flat portion 46 secured to the top wall 10 and an extension 47 held in place between the boss 17 and the adjacent portion of the web 20. This spring member is provided with a crimp or sharp bend 48 which presses strongly against the surface of the adjacent teeth of the cam wheel 24. This action 50 retards the rotation of the wheel, permitting the accumulation of greater pressure upon the finger piece 43 until the wheel reaches the position shown in Fig. 6 of the drawing. At such instant all opposition to the rotation of the wheel is removed, and simultaneously therewith the portion 49 of the bend 48 exerts a cam action on this tooth, kicking it forward in conjunction with the 55 rotary force received from the rack 41. By this action there is a short but extremely rapid movement of the cam wheel 24 and of the spark wheel 25 fixed thereto. There is thus the short but unusually intense shower of sparks against the exposed end 19 of the wick rendering its ignition certain. In this action the abrasion of the metal member 26 is reduced to a minimum due to the 60 short time of action thereon, but, on the other hand, the heating effect on the wick, although short in point of time, is abnormally intense.

The termination of this action leaves the wheel 75 24 in a position shown in Fig. 3 of the drawing.

and as the finger piece 43 is released and pressed upwardly by the spring 42 the snuffer member is pressed home against the seat 18 and the dog 35 takes its grip upon the following teeth of the wheel 24, as shown in Fig. 3. 5

It will thus be seen that there is provided a device in which the various objects of this invention are achieved and that the same is well adapted to meet the usual conditions of practical use.

As many possible embodiments may be made 10 of the above invention and as many changes might be made in the embodiment above set forth, it is to be understood that all matter hereinbefore set forth or shown in the accompanying drawing is to be interpreted as illustrative and not in a 15 limiting sense.

I claim:

1. In a lighter, a casing, a wick extending therefrom, pyrophoric material positioned adjacent said wick, a rotatably mounted friction 20 wheel, a spring forcing said material into engagement with said friction wheel, a finger piece, means effecting rotation of said friction wheel on movement of said finger piece, a spring yielding 25 resisting movement of said finger piece, and means independent of the friction wheel for interposing an additional abruptly increasing and suddenly yielding resistance to the movement of the finger piece during the latter portion of its movement. 30

2. In a lighter, in combination, a fuel receptacle having a top wall, a wick projecting above said top wall, an abrasive wheel mounted on a horizontal axis above a portion of said top wall, a pyrophoric member spring-pressed against 35 said abrasive wheel, a snuffer to cover said wick, a member carrying said snuffer mounted on the same axis as said abrasive wheel, said snuffer-carrying member having a vertical cross-section substantially like an inverted U and thereby having a substantially horizontal upper wall portion and substantially vertical side wall portions depending therefrom, said side wall portions extending downwardly on each side of said abrasive wheel and extending downwardly about said 45 snuffer, a separable finger piece mounted above said top wall and on the other side of said wheel from said wick and adapted to actuate the member carrying the snuffer and the wheel, a gear mounted on the same axis as the abrasive wheel, 50 a connection between the gear and the abrasive wheel whereby the abrasive wheel may be rotated by the gear, and a rack on that side of said gear nearest the wick to operate the gear, said rack having a portion passing under the axis of the 55 wheel and integral with the finger piece.

3. In a lighter, in combination, a fuel receptacle having a top wall, a wick projecting above said top wall and extending into said receptacle, an abrasive wheel mounted on a horizontal axis 60 above a portion of said top wall, a pyrophoric member, means pressing said pyrophoric member against said abrasive wheel, a snuffer to cover the otherwise exposed end of said wick, a finger piece mounted on a horizontal axis above said top wall, said axis being on the other side of said wheel from said wick and connected to raise said snuffer when the operating portion of said finger piece is depressed, a gear mounted on the same axis as the abrasive wheel, a connection 65 70 between the gear and the abrasive wheel whereby the abrasive wheel may be rotated by the gear, a rack in engagement with said gear on that side of the latter nearest the wick for operating the gear, said rack having a portion passing under 75

the axis of the wheel and integral with the finger piece the abrasive wheel being thereby operated to throw sparks upon the wick when the operating portion of the finger piece is manually depressed, said finger piece being substantially U-shaped in vertical cross-section to provide a top wall portion and depending vertical side wall portions, and spring means urging the operating portion of the finger piece upwardly, said spring means being accommodated substantially within and being substantially enclosed by said top wall portions and side wall portions of said finger piece, and the aforesaid connection during such upward movement being inoperative to rotate the abrasive wheel.

4. In a lighter, in combination, a fuel receptacle having an elongated top wall, a wick at one end of said top wall, an abrasive wheel mounted on a horizontal axis over said top wall, a pyrophoric member engaging an under portion of said wheel, means pressing said pyrophoric member into engagement with said wheel, a snuffer to cover said wick, a separate finger piece member mounted above said top wall and having its finger-engaging portion extending entirely to that side of said wheel opposite from the wick, means forming a well extending downwardly below said top wall in a portion of the latter adjacent to and below said wheel, a toothed member fixed coaxially to rotate with said wheel, a toothed member engaging with said first-mentioned toothed member on that side of wheel axis toward said wick and having a range of movement such that it is accommodated in said well during a portion of its path of travel and adapted upon actuation to rotate said first-mentioned toothed member and said wheel, and means whereby said second-mentioned toothed member is moved in response to actuation of said finger piece member and including a portion of the latter having a path of movement into said well.

5. In a lighter, a fuel casing having a wick, an abradant wheel rotatably mounted adjacent said wick and having pyrophoric material related thereto, a snuffer arm pivotally carried by said casing and having a snuffer cap to cover said wick, a one-way driving connection between said snuffer arm and said wheel whereby the latter is rotated only when said snuffer arm moves in a wick-uncovering direction, manually movable means having operative connection with said snuffer arm for actuating the latter in wick-uncovering direction, a member having peripheral protrusions thereon and connected to partake of rotation only when said wheel rotates, and spring means positioned in the path of movement of the protrusions of said member for interposing a yielding resistance to movement of said wheel.

6. In a lighter, a casing having a wick extending through a wall thereof, an abradant wheel mounted to rotate about an axis parallel to said

wall and having pyrophoric material related thereto, said wheel having a combined ratchet and cam wheel fixed to rotate with it, a snuffer arm pivotally carried by said casing and having a snuffer cap for covering over said wick, said snuffer arm carrying pawl means for coacting with said ratchet wheel to rotate the abradant wheel when said snuffer member moves in wick-uncovering position, a finger piece movably mounted on said casing and having operative connections whereby, upon manual actuation of said finger piece, said snuffer arm is moved in wick-uncovering direction and said pawl and ratchet means drive said abradant wheel, and spring means carried by said receptacle and projecting into the path of movement of the cam portions of said cam wheel, thereby yieldingingly to resist rotation of said abradant wheel.

7. In a lighter, in combination, a fuel receptacle having an elongated top wall, a wick extending through said top wall at one end thereof, a downwardly depressible sheet metal finger piece over the other end of said top wall and having a vertical cross-section substantially like that of an inverted U and thereby having a horizontal top portion substantially parallel to said top wall for engagement by a finger and having depending substantially vertical side wall portions, said finger piece falling within and overlying that end of the top wall over which it extends, an abrasive wheel mounted on a horizontal axis over said top wall and intermediate of the wick and finger piece member, means mounting said finger piece member for downward swinging movement, a snuffer for said wick, means comprising a sheet metal member having a top wall portion and depending vertical side wall portions and forming a complement substantially to said finger piece member in that said finger piece overlies that portion of the top wall of the fuel receptacle to one side of the wheel axis and said sheet metal member overlies that portion of the top wall to the other side of said wheel axis, the side wall portions of said means being pivoted on a horizontal axis over the casing top wall and with the top wall portion thereof extending over said wick and supporting said snuffer, said sheet metal member having its top wall portion extending over said wheel and its side wall portions extending downwardly each to one side of said wheel, a pyrophoric element projecting into contact with said wheel, and means operatively connecting said finger piece member and said sheet metal means and said abrasive wheel whereby, in response to swinging movement of said finger piece member by manual movement of its top wall portion toward said top wall of said receptacle, said sheet metal means with the snuffer is swung upwardly about the axis of said wheel and said wheel is rotated against said pyrophoric element.

CARL JULIUS LAGERHOLM.
